Francis J. Tricker of Boston, Mass

Assignor to

the Dicker Manufacturing Company of the same place

Letters Patent No. 23367. Dated July 24, 1866.

Design for a Chandelier

This design is referred to in the said letters Patent and making part of the same.

To all whom it may concern.

Be it known that S. F. J. Tricker of Boston in the County of Suffolk and State of Massachusetts have originated and produced a new Design for a bracket lamp, a sample of which the following is a full and clear descriptive, reference being had to the accompanying drawing, making part of this specification.

In the Design which is as follows in the drawing there is a swinging bracket hung upon a wall-plate a, and having a vertical arm b, and a horizontal arm c, a lamp d, being supported upon the outer end of the arm c, this lamp and the bracket having the form and ornamental configuration hereinafter claimed the Design shown and described for a swinging bracket and lamp.
